REVOLVING CALENDAR

Leo M. Jackson and William C. Murphy,
Augusta, Ga.

Application February 1, 1940, Serial No. 316,842

1 Claim. (Cl. 40—107)

This invention relates to a calendar and it aims to provide a novel construction for perpetual use.

More specifically, it provides boxes, one containing plates for days of the week and the other containing plates for days of the month adapted for sliding movement within the boxes and display at windows on opposite sides of the boxes through turning of the latter, preferably in combination with means to indicate the month and the year.

It is particularly an aim to provide illuminating means for each window of each box with novel means to control energization of the illuminating means of those windows only which are to be observed, such means also aiding to hold the boxes in proper positions to display the plates.

The more specific objects and advantages will become apparent from a consideration of the description following taken in connection with accompanying drawings illustrating an operative embodiment.

In said drawings:

Figure 1 is a view in side elevation of the calendar;

Figure 2 is a vertical section taken on the plane of line 2—2 of Figure 1;

Figure 3 is a vertical section taken on the plane of line 3—3 of Figure 1;

Figure 4 is a central vertical sectional view taken at a right angle to Figures 2 and 3;

Figure 5 is an enlarged fragmentary elevation of the controlling switch means for the lamp;

Figure 6 is a horizontal section taken on the plane of line 6—6 of Figure 5;

Figure 7 is a vertical section taken on the plane of line 7—7 of Figure 5, and

Figure 8 is an electric diagram of the lamps and their switches.

Referring specifically to the drawings wherein like reference characters designate like or similar parts, a suitable support or base is provided at 10 from which a central standard 11 and outer standards 12 rise, the same being rigidly secured to the base in any suitable manner.

Disposed for individual rotation in the spaces between the standards 11 and 12 are similar preferably rectangular boxes 13, the same having central trunnions or spindles 14 which are journaled on the standards or bearings 11 and 12.

Each box 13 at opposite side walls thereof is provided with a window or opening.

The boxes 13 are adapted to be rotated, view-

ing the same from Figure 1, forwardly and downwardly to the extent of 180°, each day so as to present a plate 16 at the window at the front of one box and a plate 17 at the window at the front of the other box. The plates 16 are seven in number, being one for each day of the week and each being so delineated and being arranged in combination with a partition 18, so as to slide within the box through rotation thereof to properly register the indications of the plates 16 at the windows.

On the other hand, the plates 17 will be of a number to present surfaces for thirty-one days and they co-act with a partition 19 and change positions through turning of the box 13 containing them, such plates 17 sliding so as to register their faces at the desired opening.

A lamp 20 is mounted on each box adjacent each window 15 in order to illuminate the same and shades 21 are preferably provided thereover.

As shown in Figure 8, one pole of the lamps 20 is grounded as at 22 while conductors 23 lead from the other poles thereof to terminals in the form of posts 24 arranged in spaced relation. Co-acting with each pair of terminals 24 is an arcuate conductor 25. The terminals 24 are mounted on the boxes 13 and the conductors 25 are mounted on the central post 11. An electric switch is provided at 26 on the base 10 connected in a power line 27, one side of which is grounded. From the switch 26, conductors 28 pass upwardly through a hollow portion 28' of the central standard 11 and thence through lateral openings 29 in the standard 11 to the conductors 25.

As a result of the construction described, it will be realized that when the boxes are in the position of Figure 1, only those lamps 20 which can be viewed from the front of that figure are illuminated because one terminal 24 of each box only is in contact with the arcuate conductor 25 associated therewith, such conductor being spaced from the other co-acting terminal 24. However, when the boxes are moved forwardly and downwardly 180°, in automatically changing the plates 16 to successive days and the plates 17 to successive dates, the conductors 25 will be disengaged by the contacts 24 mentioned and will be engaged by the other contacts 24, thus illuminating the windows automatically for the cards of the succeeding days while automatically extinguishing the light at the window for the previous day.

Attention is also called to the fact that the terminals 24 engage the contacts or conductors 25 with a certain amount of friction, aiding in

holding the boxes against displacement from perpendicular positions.

In addition to the indications of the days of the week, a drum is provided at 30 which has month delineations or indications thereon at 31 to register with a window 32 in a hollow cylinder 33. Such cylinder 33 is fastened as at 34 between the post 11 and one of the posts 12 and to the latter. A rotatable operating rod 35 is journaled in the latter post 12 and one end wall of the cylinder 33 and is rigidly connected to the drum 30 so that through rotation of the rod 35, the drum 30 will be rotated to register the proper month indication at window 32, the parts being in sufficient frictional contact to remain in adjusted positions.

The year may also be indicated since a drum is provided at 36 provided with year indications 37 peripherally thereof adapted to be registered at an opening 38 in a hollow cylinder 39 located between the other standard 12 and the post 11 and fastened for instance to the former by screws as at 40. An operating rod 41 extends from the drum 36, being journaled in one end wall of the cylinder 39 and in the said standard 12, sufficient friction being provided between the parts to maintain the drum 36 in its different positions against accidental displacement. Each of the drums 30 and 36 also preferably has a spindle at its inner end at 42 and 43, journaled 30

in adjacent end walls of the cylinders 33 and 39.

Various changes may be resorted to provided they fall within the spirit and scope of the invention.

We claim as our invention:

A calendar of the class described having a post member, a box member rotatable on the post member on an axis disposed laterally with respect to the post member, said box member having windows on opposite sides thereof, lamps carried by the box member one to illuminate each window, plates operable within the box member for display at said windows at the same relative location through rotation of the box member, a pair of pin-like terminals extending laterally from one of said members having conductors leading to the lamps, an arcuate conductor extending laterally from the other of said members and concentric with the axis of rotation of the box member, said arcuate conductor being constructed and arranged to frictionally engage with one terminal at a time whereby only one lamp will be illuminated at a time and when at said location, the frictional engagement between the terminals and the arcuate conductor being of a degree to aid in holding the box member in its different positions.

LEO M. JACKSON.

WILLIAM C. MURPHY.
